DESIGN.

A. ST. GEORGE.
BOTTLE.

No. 27,884.

Patented Nov. 23, 1897.

UNITED STATES PATENT OFFICE.

AUGUST ST. GEORGE, OF CHICAGO, ILLINOIS, ASSIGNOR TO GEORGE BENZ & SONS, OF ST. PAUL, MINNESOTA.

DESIGN FOR A BOTTLE.

SPECIFICATION forming part of Design No. 27,884, dated November 23, 1897.

Application filed October 15, 1897. Serial No. 655,353. Term of patent 14 years.

To all whom it may concern:

Be it known that I, AUGUST ST. GEORGE, a citizen of the United States of America, residing at Chicago, Cook county, Illinois, have invented and produced a new and original Design for Bottles, of which the following is a specification, reference being had to the accompanying drawings, forming a part thereof.

In the drawings, Figure 1 is an elevation of one side of a bottle, showing my new design; Fig. 2, a detail elevation of one corner of the bottle, and Fig. 3 a plan view of the same.

As shown in the drawings, a bottle made in accordance with my design consists of a body portion A, which is approximately one and one-third times as long as its greatest breadth. This body portion has a convex top A' and rounded bottom edges, as shown at A², the corners A³ being chamfered, as shown, and each provided with a rib A⁴, extending to the bottom of the bottle. The sides of the body portion are paneled, as illustrated at A⁵. The neck B is provided at its connection with the body portion with a molding B', and at its upper end has an enlargement B² in the form of a conical frustum. The body portion is or-

namented in relief with conventional patterns, as shown, while the panels may be plain. The ornamentation shown on the body portion is particularly characterized by the fact that the upper end of each chamfered corner meets a conventional shell pattern A⁷, while intermediate the sides of the body portion and above and below the panels are placed conventional lilies. The remaining ornamentation is in the nature of scrolls or conventional vines and leaves. Around each panel the background is corrugated, as shown at A⁸. The top of the body portion has a series of elliptical ornaments A⁹, arranged in a circle concentric with the bottle-neck and outside the molding B'.

Having described my invention, what I claim as new, and desire to secure by Letters Patent, is—

The design for a bottle as herein shown and described.

In testimony whereof I affix my signature in presence of two witnesses.

AUGUST ST. GEORGE.

Witnesses:

THOMAS CHRISTIANSON,
FRITZ FRANTZEN.
